CLAIM

We claim the ornamental design for an electronic device, as shown and described.

DESCRIPTION

FIG. 1 is the front perspective view of an electronic device showing our new design;

FIG. 2 is the front view thereof;

FIG. 3 is the rear view thereof;

FIG. 4 is the left-side view thereof;

FIG. 5 is the right-side view thereof;

FIG. 6 is the top-side plan view thereof;

FIG. 7 is the bottom-side plan view thereof;

FIG. 8 is another front perspective view of the electronic device, in which features are provided in broken lines to illustrate an example of the electronic device in use;

FIG. 9 is another front perspective view of FIG. 8, in which the electronic device is provided in an unfolded position to illustrate another example of the electronic device in use;

FIG. 10 is an enlarged view of the encircled portion shown in FIG. 9;

FIG. 11 is an enlarged view of the encircled portion shown in FIG. 9;

FIG. 12 is an enlarged view of the encircled portion shown in FIG. 9; and,

FIG. 13 is an enlarged view of the encircled portion shown in FIG. 9.

The broken lines in the figures show portions of the electronic device which form no part of the claimed design. The dot-dot-dash broken lines encircling portions of the claimed design that are illustrated in enlargements form no part of the claimed design.
